UNITED STATES PATENT OFFICE.

OTTO F. HINTZ, OF DETROIT, MICHIGAN, ASSIGNOR TO FARRAND ORGAN COMPANY, OF DETROIT, MICHIGAN, A CORPORATION OF MICHIGAN.

ADJUSTABLE TRACKER FOR PIANO-PLAYERS.

No. 920,571.

Specification of Letters Patent.

Patented May 4, 1909.

Application filed February 24, 1903. Serial No. 144,903.

To all whom it may concern:

Be it known that I, OTTO F. HINTZ, residing at Detroit, in the county of Wayne and State of Michigan, a citizen of the United States, have invented certain new and useful Improvements in Adjustable Trackers for Piano-Players, of which the following is a specification, reference being had therein to the accompanying drawings.

10 The invention relates to pneumatic players for musical instruments, and has more particular reference to the construction of the tracker.

15 In the present state of the art various forms of pneumatic players have been devised, all of which employ a perforated music sheet and tracker bar over which said sheet is fed, in which is formed a series of ports leading to the pneumatics. In different 20 makes of instruments the range of ports in the trackers is not always uniform, and as a consequence the music which is constructed for the one make of instrument cannot be employed on the other.

25 It is the object of the present invention to obtain a construction of tracker which is adapted for use with music of different registration, and to this end the invention consists in the peculiar construction of a tracker 30 which has an adjustable range, and further in the peculiar construction, arrangement and combination of parts, as hereinafter described and claimed.

35 In the drawings Figure 1 is a vertical cross section through one form of tracker to which my improvements are applied showing in connection therewith the music sheets and rolls. Fig. 2 is a sectional front elevation of the tracker shown in Fig. 1. Fig. 3 is a longitudinal section through a portion of a 40 tracker of modified construction, Fig. 4 is a cross section therethrough. Fig. 5 is a plan view of the lower or permanent section of the tracker, and Fig. 6 is a perspective view of the upper or exchangeable section of the 45 tracker.

In the construction shown in Figs. 1 and 2 A indicates the music holding roll and B the winding roll of a pneumatic player. C is a 50 tracker which may be of any ordinary construction, being provided with the ported face strip D over which the music sheet E is adapted to travel.

55 In normal operation the music sheet E is drawn from the roll A over the strip D and

to the roll B as indicated by the dotted line in Fig. 1. Where it is desired to use music of different registration or range an auxiliary tracker section F is used, which is adapted to fit upon the ported face strip D of the tracker C. The section F has formed therein a series of passages a, which on the inner face of the section are adapted to register with the corresponding ports b in the strip D. The outer face c of the section F is provided with a series of ports d which are of different registration from the series of ports b. The passages a are inclined at different angles so as to connect the ports in the series b with its corresponding ports in the series d.

The auxiliary section F of the tracker may be secured in position in any suitable manner, such as by means of bolts G secured to the main tracker C and engaging with apertures in the section F. The outer ends of these bolts are threaded for the engagement of the winged nuts H by means of which the section F may be firmly clamped against the section C.

In operation the music sheet from the roll holder A may be drawn around the face strip of the auxiliary section F and thence to the winding roll B, as shown in full lines in Fig. 1.

The range of the port d being adapted to register with the music for which the auxiliary section is designed, it is evident that the operation will be the same with music of this character as with sheets constructed for the regular tracker C.

In Figs. 3, 4, 5 and 6 is illustrated a modified construction in which the tracker is formed in separable sections, and a plurality of interchangeable outer or detachable sections are provided for use with a common stationary section. As shown, I is the stationary or permanent section of the tracker which is preferably formed with staggered ports e passing therethrough. These ports may be formed by boring and may be connected by nipples f with the conduits J leading to the pneumatics, not shown. By boring these ports e and staggering them they may be made of much larger area than would be possible if placed in a single line. K and K' are interchangeable detachable sections, which on their inner faces are provided with a series of ports g, arranged to register with the ports e in the section I. The ports g are connected by inclined passages h and h' with

the ports *i* and *i'* formed respectively in the face strips of the sections *K* and *K'*.

The sections *K* *K'* are preferably formed of the subsections *j*, *k*, *l* *l'*, and *m* *m'*, as illustrated in Fig. 4. The subsection *j* is bored to have its ports *g* register with ports *e*. The section *k* has the passages *h* formed therein, preferably by kerfing it upon opposite sides, as indicated by full and dotted lines in Fig. 4. These passages are inclined oppositely in the sections *K* and *K'*, so that in the section *K* the range of ports *i* is of greater length than the ports *e* in the section *I*, whereas in the section *K'* the range of ports *i'* is of lesser length than in the section *I*. This opposite inclination of the passages of the sections *K* *K'* is not essential, but it is desirable for the reason that the angle is not as great in either section as it would be if the other section were formed with parallel passages.

To prevent the possibility of leakage of air, one or the other of the adjoining faces of the sections *I* and *K* *K'* is provided with a facing such as *n* of any suitable packing material.

In use the sections *K* and *K'* may be exchanged one for the other and may be secured in position on the section *I* by any suitable means, such for instance as the dowel pins *O* and clamping means, either as shown in Figs. 1 and 2 or of any suitable construction.

I have used the term "range" in these specifications to indicate generally the variance of the transverse positions of the inlets to the ducts of the removable tracker boards and also the transverse arrangement of the perforations of the music sheet. In certain music sheets or rolls the position of the per-

forations vary relative to each other transversely and in some the maximum distance between the extreme outside lines of perforations vary from that of music rolls or sheets of different manufacture and it is this transverse spacing of the perforations either in the sheets or tracker board sections that I have designated the "range".

What I claim as my invention is:

1. The combination in a musical instrument player of a plurality of trackers having their ducts spaced respectively in relatively different ranges, and means for locating and securing either of said trackers in operative position on the instrument.

2. In a mechanical musical playing instrument the combination with a duct section, of means associated therewith for varying transversely the range and position of the inlet ports of said ducts.

3. The combination with a main duct section, of a mechanical musical instrument, of movable means associated with said section for varying the transverse range of the inlet openings to said duct section, and means for securing said movable means fixedly in place.

4. A tracker in combination with a duct section of means for changing the range of the entire series of inlet ports, and means for securing said changing means fixedly in adjusted position.

In testimony whereof I affix my signature in presence of two witnesses.

OTTO F. HINTZ.
